UNITED STATES PATENT OFFICE.

WILLIAM HENRY THOMPSON AND ROBERT THOMPSON, OF LONDON,
ENGLAND.

INTERCHANGEABLY-LOCKED GEARING.

SPECIFICATION forming part of Letters Patent No. 752,129, dated February 16, 1904.

Application filed December 22, 1902. Serial No. 136,228. (No model.)

To all whom it may concern:

Be it known that we, WILLIAM HENRY THOMPSON and ROBERT THOMPSON, subjects of the King of Great Britain, residing at 155 5 Fenchurch street, in the city and county of London, England, have invented a certain new and useful Improvement in Interchangeably-Locked Gearing, of which the following is a full, clear, and complete specification.

This invention relates to motor-driven vehicles; and it consists of an improved multiple speed-gear and of means for operating and controlling the same.

In the accompanying drawings, which are given by way of illustration only, Figure 1, Sheet No. 1, is a view in elevation, partly in section. Fig. 2, Sheet No. 1, is a view in plan, partly in section, looking from the under side of Fig. 1. Fig. 3, Sheet No. 2, is a view in side elevation, partly in section. Fig. 4, Sheet No. 3, is a view in elevation, showing the reverse side to Fig. 1, the case being partly in section; and Fig. 5, Sheet No. 3, is a view of the index of the locking quadrant 25 or sector.

Similar letters refer to similar parts throughout the several views.

According to this invention a differential or "balance-geared" axle is employed on which 30 is loosely mounted a spur-wheel B capable of being made fast to the said axle by a clutch C, either of the sliding type, as shown, or of any other suitable type. Any suitable form or type of differential or balance-geared axle, of 35 which there are many well known, may be employed. On the axle A, hereinafter called the "central" or "driven" axle, is pivoted a swinging carriage D, carrying a pinion E, engaging and gearing with the spur-wheel B on 40 the axle A. Mounted on the same axle as the pinion E or made in one with it, so that they operate together, is a pinion F. Mounted also on the carriage D is another pinion, G, of the same size as the pinion F and always in 45 mesh with it. The central axle A is mounted in bearings carried by or forming part of a suitable case H, adapted to inclose the gear, and in this case are mounted at an equal and predetermined distance from the center of the axle A as many axles as changes of speed are

required. In the accompanying drawings five such axles are shown, thus providing for five changes of speed. These axles preferably consist of stud-axes J', J², J³, J⁴, and J⁵, on which are mounted hollow or sleeve axles K', K², K³, K⁴, and K⁵; but although this construction is preferred on account of simplicity of construction and ease of renewal of the gear-wheels free axles running in suitable bearings may be employed. On these axles are mounted pinions L, M, N, O, and P, which are all of equal size and have the same number of teeth. The position of these axles with respect to the axle A is such that by rocking the carriage D the pinions F and G 65 can be brought into engagement with any of the pinions L, M, N, O, and P.

On the axle K' is mounted a spur-pinion q, which gears with a spur-wheel R on the axle K². On this axle K² is also a spur-pinion r, which 70 gears with a spur-wheel S on the axle K³. On this axle K³ is also a spur-pinion s, which gears with a spur-wheel T onto the axle K⁴. On this axle K⁴ is also a spur-pinion t, which gears with a spur-wheel U on the axle K⁵, the 75 arrangement being such that the speed of each succeeding axle after the axle K' is reduced a predetermined amount.

The motor of whatever type is employed drives the sleeve-axle K' through the axle K, 80 which is mounted in suitable bearings in or on the case H, or alternatively the pinions L and q may be mounted direct onto the axle K. The motor may either be connected direct to the axle K, as shown in Fig. 1, or it may be 85 connected indirectly thereto, according to the disposition of the parts on the vehicle.

It will be seen that as all the axles K', K², K³, K⁴, and K⁵ are geared together by the train of wheels q, R, r, S, s, T, t, and U the 90 pinions L, N, and P will revolve in one direction and the pinions M and O in the reverse direction. If, therefore, the carriage D is set to engage the pinion F with either of the pinions L, N, and P, the axle A will be driven in 95 one direction at one of three different speeds, and if the pinion F is engaged with the pinions M and O the axle will be driven in the reverse direction at one of two different speeds. If, however, the pinion G be engaged with 100

either of the pinions M or O, the axle A will be driven at one of two different speeds in the same direction as it was driven when the pinion F was engaged with either of the pinions 5 L, M, and P, whereas it will be driven at one of three different speeds in the reverse direction if the pinion G is brought into engagement with either of the pinions L, N, and P.

To enable the carriage D to be moved to bring one or other of the pinions F and G into engagement with the pinions L, M, N, O, and P, the carriage is connected either directly or indirectly with a lever V, working in a quadrant W or its equivalent, whereby it can be 15 rocked about the axle A and locked in the position to give the desired speed and direction. The lever V is provided with a trigger-rod V', carrying a tooth v, adapted to engage detents w in the quadrant W or its equivalent, so as 20 to retain the carriage in the desired position to engage the pinions F or G, as the case may be, with one or other of the pinions L, M, N, O, and P, according to the speed at which and the direction in which the axle A is to be 25 driven. The quadrant or sector W is provided with an index, as shown in Fig. 4, to indicate the positions of the lever V for the different speeds ahead and astern.

The sliding clutch C is operated by a bell- 30 crank lever X, pivoted to the rocking carriage D, the said bell-crank lever being coupled to the trigger-rod v' the arrangement being such that the trigger is always in engagement with the quadrant or sector until the clutch is put out of gear with the wheel on the driven axle, or, 35 in other words, that the position of the rocking carriage cannot be altered so long as the spur-wheel on driven axle is fixed thereto by said clutch.

40 The carriage D may be operated by an index-wheel instead of by a lever, the said wheel operating through a shaft and gearing and being fitted with the locking-trigger and mechanism for operating the clutch, as before described.

45 What we claim, and desire to secure by Letters Patent, is—

1. In a motor-driven vehicle, a multiple speed-gear comprising an axle to be driven, a 50 spur-wheel loosely mounted on said axle, a clutch for coupling said wheel to said axle, a carriage pivoted on said axle, a pinion mounted on said carriage and gearing with spur-wheel on said axle, two pinions of equal size 55 mounted on said carriage so that they gear with one another one of said pinions being connected to the pinion gearing with spur-wheel on driven axle, a group of axles arranged radially with respect to driven axle 60 and at equal distances therefrom, spur-pinions on said axles with which the two pinions in gear with one another and mounted on said carriage can be engaged by rocking said carriage on said axle, a train of gearing connecting the group of radially-arranged axles with one another so that 65 the speed of each succeeding one after the first—which is the driving-axle—is reduced a predetermined degree, a case inclosing said gear, a lever for operating rocking carriage, a quadrant over which said lever travels, a trigger-rod for locking said lever to said quadrant, and a connection for operating the clutch locking the spur-wheel on driven axle to said axle, as set forth.

WILLIAM HENRY THOMPSON.
ROBERT THOMPSON.
